UNITED STATES PATENT OFFICE.

GEORGES ROTH, OF VIENNA, AUSTRIA-HUNGARY.

AUTOMATIC FIREARM

SPECIFICATION forming part of Letters Patent No. 616,260, dated December 20, 1898.

Application filed July 15, 1897. Serial No. 644,652. (No model.)

To all whom it may concern:

Be it known that I, GEORGES ROTH, a citizen of Austria, residing at Vienna, Austria-Hungary, have invented certain new and useful Improvements in Automatic Firearms, (for which I have obtained patents in Austria, dated January 24, 1896, No. 46,296; in Hungary, dated January 29, 1896, No. 5,308; in Germany, dated November 19, 1895, No. 91,313; in France, dated November 19, 1895, No. 251,848; in Belgium, dated November 19, 1895, No. 118,443; in England, dated November 19, 1895, No. 22,018; in Italy, dated January 3, 1896, R. G., Vol. XXX, No. 40,266; R. A., Vol. LXXIX, No. 49; in Switzerland, dated Nov. 19, 1895, No. 11,334, and in Spain, dated April 25, 1896, No. 2,135,) of which the following is a specification.

This invention relates to the construction of an automatic quick-firing magazine gun, in which the recoil, after firing, moves back the barrel, the receiver, and the breech-bolt simultaneously in their closed position to a distance exceeding the length of a cartridge, in which position they are held by a stop-lug actuated by the trigger and by a stop-piece abutting against the hammer as long as the trigger is held back. This retention of the receiver and the breech-bolt occurs under all circumstances, even when the trigger is released as quickly as possible after firing, because the finger holding the trigger cannot be moved with the same velocity as the parts are moved by the recoil, the result being that the discharge of the gases is always forward and not rearward, whereby the fouling of the receiver and the breech-bolt is prevented and the firearm always remains clean and ready for firing even after a great number of shots.

When the trigger is released, the receiver and the breech-bolt are separately pushed forward in such a manner as that the barrel and receiver, operated by a spring, are first brought forward, and when they are nearly at the end of their course the breech-bolt follows, being actuated by a second spring, the difference of time between such forward movements being taken advantage of for ejecting the cases and for inserting a new cartridge.

In the accompanying drawings, Figure 1 is a side elevation of my improved firearm, the

cover of the frame being removed, the barrel, the receiver, and breech-bolt being in their forward position, and the magazine being omitted. Fig. 2 is a vertical longitudinal section of the gun, the magazine being removed. Fig. 3 is a partial horizontal section, the barrel, receiver, and breech-bolt being in their rearward position. Fig. 3^a represents a vertical longitudinal section, the barrel and the receiver being in their forward position. Fig. 3^b is a vertical transverse section. Figs. 4, 5, and 6 represent in side view, longitudinal section, and plan view, respectively, the stop-lug actuated by the trigger with its operative lever. Fig. 7 is an end view, and Fig. 8 a vertical cross-section, of the same. Fig. 9 is a plan view of the lever which carries the stop-lug. Figs. 9^a, 9^b, and 9^c show detail side views of the lock mechanism consisting of the trigger, hammer, and the regulator. Fig. 9^a indicates the position at the point of the first stop—that is to say, the position in which the parts are placed by the rearwardly-drawn receiver. Fig. 9^b indicates the position of the parts at the moment of firing, and Fig. 9^c after firing, in which the hammer is in its terminal position and the trigger and the regulator disconnected from each other. Fig. 10 is a longitudinal section of a modification of the breech-lock and stop mechanism in a closed position and in that position in which the hammer is released at the moment of firing. Fig. 11 represents a similar view to Fig. 10 after firing, but before the beginning of the rearward movement of the parts. Fig. 12 represents the position of the several parts after the completed rearward movement of the breech-bolt, and Fig. 13 represents the same parts when the receiver is stopped and the breech-bolt somewhat loosened. Fig. 14 illustrates the limitation of the movement of the hammer during the back movement of the breech-bolt. Figs. 15 and 16 represent the mainspring in elevation and under side view. Figs. 17, 18, 19, and 20 show the pressure-thumb of the trigger in three different elevations and in cross-section, respectively. Figs. 21 and 22 are vertical longitudinal sections, taken at right angles to each other, of the breech-bolt, firing-pin, and ejector. Figs. 23, 24, 25, 26, and 27 are detail views of the abutment for limiting the backward motion

of the receiver; and Figs. 28, 29, and 30 are detail views of the stop-spring in three different elevations.

Similar letters of reference indicate corresponding parts.

Referring to the drawings, the barrel *b* is screwed into the receiver *c* in the usual manner and slides with the latter in the frame *a* and is constantly pressed forward by a spring *b'*, bearing at one end against a fixed projection *a'* of the frame *a* and at the other end against the barrel-cap *b²*.

In the axial bore of the receiver *c* is the breech-bolt *d*, carrying a firing-pin *d⁶*, with spring *d⁷* and cartridge-extractor *d²*. The said breech-bolt is continually subjected to the forward pull of a draw-bar *f*, acted upon by a spiral spring *f²*, sleeved on the stationary guide-rod *f'*, arranged in the frame *a*.

20 By the recoil due to the explosion on firing, the receiver *c*, together with the barrel *b* and breech-bolt *d*, is thrown back as far as the breech-bolt is drawn back in present guns to eject the exploded cartridge. A lug *e* (shown in Figs. 23 to 27 in detail) is located on the exterior frame *a* at the rear of the breech end of the same and is provided with an abutment or cheek *e'*, that passes through a longitudinal

25 groove *c⁵* at one side of the receiver *c*, so that a lug *d³* on the breech-bolt *d*, which enters partly into the groove *c⁵*, can move with the breech-bolt *d* during the backward motion of the same until it moves against the abutment or cheek *e'*. The lug *d⁸* of the breech-

30 bolt *d* forms at the same time a connecting-piece between the receiver and breech-bolt *d*, inasmuch as the lug *d⁸* enters into a recess at the front part of the groove *c⁵*, so as to be placed in front of a shoulder *c⁴* on the receiver

35 *c*, so that by the action of the gases of combustion on the face of the breech-bolt *d* the latter is moved backward, and the lug *d³* is thereby pressed against the shoulder *c⁴*, so as to move the receiver along.

40 45 At the end of the simultaneous backward motions of the receiver *c* and the breech-bolt *d* a wedge-shaped projection *g'*, located on the stop-spring *g*, attached back of the guide-rod *f'* to the exterior frame *a*, snaps into a notch *f⁸* of the draw-bar, said projection *g'* thereby preventing the breech-bolt *d* from moving forward for a sufficient time until the receiver *c*, which moves independently of the breech-bolt *d* in forward direction, has moved over

50 55 the entire distance. At the end of the forward movement of the receiver the same presses by its under side against an inclined projection *g²* on the stop-spring *g* and moves the latter sidewise far enough so that the

60 65 wedge-shaped projection *g'* is moved clear of a notch *f⁸* of the draw-bar *f*, whereby the latter is released, so that under the influence of its spring *f²* it moves the breech-bolt *d* forward and accomplishes the closing of the breech. As the backward movements of the

60 said parts take place independently of each other, it is necessary that the above-mentioned connection between the receiver *c* and breech-bolt *d* be broken. For this purpose an inclined loop *f⁴*, located on the draw-bar *f*, is used, by which loop the draw-bar is connected with the pin *d⁶* of the breech-bolt *d*. At the end of the backward movement the breech-bolt *d* is prevented, as before mentioned, from moving again in forward direction by the engagement of the spring projection *g'* in the notch *f⁸* of the draw-bar *f*. The receiver *c* and barrel are, as soon as the trigger is released by the finger, under the influence of the spring *b'*, which pulls the same, together with the barrel *b*, in forward direction. The spring *b'* now presses reversely and tends to carry the breech-bolt 85 along, but is prevented therefrom by the draw-bar *f*. The inclined loop *f⁴* permits the breech-bolt to have a certain longitudinal motion, which is carried out by the same, but during which motion the inclination of the loop *f⁴* 90 compels the breech-bolt *d* to make an axial rotation, so that the projection *d⁸* is placed out of reach of the projection *c⁴*. In this manner the connection of the receiver *c* and breech-bolt *d* is discontinued, and the former can move forward, while the projection *d⁸* of the breech-bolt *d* is received in the longitudinal groove *c⁵* of the receiver. A pin *c⁶* on the lower rear part of the receiver *c* projects into a groove *d⁴* of the breech-bolt and serves as 100 a guide for the breech-bolt *d* during its forward movement.

105 By drawing back the trigger *i*, pivoted at *i'*, a projection *i²* thereof actuates the lever *m* of the stop-lug mechanism, which turns on a pin *m'*, fixed to frame *a*, and which engages by a hook *m²* on the rear end of the lever *m* with a projection *c⁸* in the lower rear part of the receiver *c* when in backward position, and thus keeps the latter, as also the barrel, in 110 that position as long as a pull is exerted on the trigger *i*. When the trigger *i* is released, the stop-lug *m m²* is moved back by a spring *m³*, confined between the top part *a²* of the frame *a* and the lever *m*, and thereby releases 115 the receiver *c*, which is now thrown forward by the spring *b'*.

120 The hammer *h* turns on a pivot-bolt *h⁶* and is under the influence of the mainspring *r*, which is located in the frame *a* and is under the influence of the trigger *i*. The trigger is provided with a thumb *i³*, which turns on a pin or bolt *i⁴* on the inner end of the trigger, said thumb acting on a tooth *h⁵* of the hammer *h*, which tooth projects from the lower 125 end of the hammer. The hammer *h* is also provided below its head with a recess, in which is arranged a pivoted tongue *h'*, used as a setting device. The tongue *h'* is made tapering or pointed at its outer end and is so located that said end overlaps the catch-flange *h²* of the hammer, which flange is located at the back of the hammer and is made in the nature of a small hook, with which the hammer- 130

regulator *k*, that is pivoted to a frame *a* at a point below the hammer, engages, so that the engagement of the hammer-regulator *k* into the hook-shaped portion of the flange *h*² is prevented during the firing.

My improved lock mechanism is operated as follows: It is assumed that the hammer has completed its motion and that the parts *h*, *i*, and *k* of the lock have assumed the position shown in Fig. 9^a. By the recoil the breech-bolt is moved in backward direction, while the inclined portion *c*¹, which is located at the lower side of the receiver *c*, acts on the head of the hammer and throws the hammer in backward direction. The flange *h*² is thereby caused to pass the hammer-regulator *k*, which is pressed against the hammer *h* by the spring *k*² and is placed under the hook *k*¹ of the regulator, so that at the next following forward motion of the hammer *h*, under the tension of the mainspring *r*, the flange *h*² is engaged by the hammer-regulator *k*, so that the same is thereby held in retracted position. It must be observed in this connection that the hammer *h* can only be moved back to such an extent that the hammer-regulator *k* does not pass beyond the tongue *h*¹, as otherwise the entire throw of the hammer would take place, as will be described hereinafter. After the breech-bolt has completed its backward motion the barrel *b* and receiver *c* are moved forward, during which motion the shell of the cartridge is ejected by the extractor *d*². As soon as the barrel *b* and receiver *c* arrive at the end of their motion the breech-bolt *d* follows and simultaneously moves a new cartridge into the barrel *b*. The firearm is now ready for the next shot and can be fired by pulling the trigger *i*, the parts of the lock then having the position shown in Fig. 9^a. During the pulling of the trigger the thumb *i*³ of the same presses against the tooth *h*³ of the hammer *h* and pushes the same in backward direction while imparting a tension to the spring *r*. The hammer-regulator *k* then passes over the tongue *h*¹, which has moved into position so as to overlap the flange *h*². By the continued pull on the trigger *i* the thumb *i*³ is finally placed out of engagement with the tooth *h*³ (see Fig. 9^b) and the hammer released, so that the parts *h*, *i*, and *k* again assume the positions shown in Fig. 9^a. The tongue *h*¹ thereby prevents the engagement of the hammer-regulator *k* with the flange *h*², and thereby facilitates the release of the hammer.

In Figs. 10 to 13 is illustrated a modified construction of the gun, in which the retention of the closed breech-bolt when moved back by the exploding gases is not effected by a special stop-lug *m*, actuated from the trigger, but by the hammer-head *h*⁴ of the hammer under the action of the lock-spring *r*. This result is obtained by omitting the catch-flange *h*¹ and tongue *h*² of the hammer *h* and also the regulator *k*, so that the hammer *h* remains under constant tension of the

spring *r*. The spring *r* bears with the one extremity *r*² against the projection *h*⁵ of the hammer *h*, while with the second extremity *r*³ it bears against the pressure-thumb *i*³ of the trigger *i*, so that the spring *r* is free to move toward both sides—that is to say, a pressure or resistance exerted upon one side is counterbalanced on the other side. When the trigger *i* is under the tension of the main spring *r*, the free extremity *r*² of the said spring presses against the projection *h*⁵ of the hammer *h* and turns the same upward on its pivot *h*⁶, so that the hammer-head *h*⁴ is pressed toward the lower side of the receiver *c*, or it may snap into a cavity of the same in front of the inclined surface *c*¹.

By pressing on the trigger *i* the hammer-head *h*⁴ is brought to full-cock. (See the position shown in Fig. 11.) By the recoil the barrel *b*, receiver *c*, and breech-bolt *d* are forced backward. The inclined surface pushes the hammer *h* backward at the same time, whereby the lock-spring *r* is placed under tension. (See Fig. 12.) As the trigger offers no resistance the spring *r* forces the hammer *h* forward, and the hammer-head *h*⁴ snaps in front of the inclined surface *c*¹ of the receiver *c* and prevents it from moving forward. (See the position shown in Fig. 13.) When the trigger *i* is released and arrives at the end of its return movement in its cocked position, the hammer-head *h*⁴ of the hammer is released, so that the receiver *c* and the breech-bolt *d* move forward. The releasing of the hammer *h* is also effected by the main spring *r*, which latter, with its enlarged part *r*⁴, Figs. 15 and 16, engages behind the tapering projection *h*⁷ of the hammer *h*. When the trigger is released, at first the free end *r*³ of the spring *r* presses against the pressure-thumb *i*³ of the trigger *i*, and when the latter has arrived nearly at the end of its rearward movement the enlarged spring part *r*⁴ presses against the projection *h*⁷, effecting the turning of the hammer about its pivot *h*⁶ in the direction shown by the arrow, (see Fig. 13,) and also effecting a disengaging of the hammer-head *h*⁴.

Owing to the forcible action of the exploding gases the hammer *h* would be thrown back so far that the same could not return to its former position only when the casing had already moved forward, and it was hence necessary to provide means to prevent this excessive backward movement. This means consists of a projection *r*⁵ on that side of the mainspring *r* toward the hammer *h*, against which projection *r*⁵ the surface *h*⁸ of the hammer is adapted to bear. This position of the device is shown in Fig. 12, and is also illustrated for the sake of clearness on an enlarged scale in Fig. 14.

By beveling the pressure-thumb *i*³ of the trigger *i* on the side *i*⁶ opposite the end *r*³ of the mainspring *r*, (see Figs. 17 to 19,) so that the spring *r* is moved downward toward the rear wall of the frame, the result will be

that as soon as the trigger reaches the position shown in Fig. 11 in relation to the pressure-thumb r^3 it slides on the inclined surface i^6 .

- 5 Supposing the trigger i be held back by the finger of the operator, then as the finger cannot be moved as quickly as the parts of the lock mechanism and the breech-bolt are moved by the exploding gases the hammer h 10 will successively occupy the following positions: Fig. 10, the cocked position; Fig. 11, the position at the moment of firing; Figs. 12 and 14, the position at the end of the recoil movement, limited by the lug or projection 15 r^6 , and, finally, as shown in Fig. 13, the stopping position of the receiver. The rearward movement of the spring end r^3 , so that the same bears again upon the pressure-thumb r^3 , is effected by the latter itself, as the bevelled surface i^5 , Figs. 18 and 19, on the fore end of the pressure-thumb r^3 bears under the projection r^5 when the trigger i is turned and lifts the projection r^5 , so that the spring r again arrives in its normal position, Fig. 10. 20
- 25 By the closing of the barrel while in backward position the powder gases are forced, as before stated, to discharge at the front of the barrel, so that a fouling of the breech-bolt, &c., is prevented and the firearm remains 30 clean and ready for firing, even after a very great number of shots. The construction described may be employed for all kinds of firearms, and the form, size, and the internal construction of the barrel, whether rifled or not, 35 may be varied at will.

Having now described my invention, what I claim is—

1. In recoil-operated firearms, the combination with a movable receiver and a movable breech-bolt, simultaneously operated by the recoil, of means for retaining the breech-bolt at the limit of its rearward movement, means for retaining the receiver at a point less than the limit of its rearward movement, and

means for simultaneously releasing and returning the receiver and breech-bolt to the firing position, substantially as set forth. 45

2. In recoil-operated firearms, the combination of a movable receiver and a movable breech-bolt, simultaneously operated by the recoil, of a pivoted stop-lug operated by the trigger for retaining the receiver in its rearward position, a bevelled or inclined portion on the receiver adapted to engage the head of the hammer, and means for releasing and returning the receiver and breech-bolt, substantially as set forth. 50

3. In recoil-operated firearms, the combination with a movable receiver, and movable breech-bolt, simultaneously operated by the recoil, of a draw-bar connected with the breech-bolt and provided with a notch, a stop-spring for engaging the notch of said draw-bar and holding the breech-bolt at the limit of its rearward movement, means for retaining the receiver at a point in advance of the limit of its rearward movement, and means for simultaneously releasing and returning the receiver and the breech-bolt to firing position, substantially as set forth. 60

4. In recoil-operated firearms, the combination with a movable receiver and a movable breech-bolt, simultaneously operated by the recoil, said receiver being provided with a bevelled lug, of a hammer having a hammer-head adapted to engage with said lug, a double-lock spring adapted to operate said hammer, a trigger and a pressure-thumb pivoted to the trigger and against which one end of the lock-spring bears, said pressure-thumb being adapted to be gradually released from the hammer, substantially as set forth. 75

In testimony whereof I sign this specification in presence of two subscribing witnesses.

GEORGES ROTH.
